Primary Examiner — Holly E Thurman*Assistant Examiner* — Bobby W Jones, II(74) *Attorney, Agent, or Firm* — Law Offices of Sandy Lipkin; Sandy Lipkin(57) **CLAIM**

The ornamental design for a fire sprinkler cover as shown and described.

DESCRIPTION

FIG. 1 is a front, right and top perspective view of a fire sprinkler cover, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view of the fire sprinkler cover of FIG. 1, taken along section line 9-9 as depicted in FIG. 7.

1 Claim, 9 Drawing Sheets(56)
